UNITED STATES PATENT OFFICE.

WILLIAM TWEEDDALE, OF BROOKLYN, ASSIGNOR TO THE NORTH AMERICAN IRON WORKS, OF NEW YORK, N. Y..

DESIGN FOR A VASE.

SPECIFICATION forming part of Design No. 13,619, dated February 13, 1883.

Application filed December 22, 1882. Term of patent 7 years.

To all whom it may concern:

Be it known that I, WILLIAM TWEEDDALE, of Brooklyn, in the county of Kings and State of New York, have invented a new and ornamental Design for Vases, of which the following is a specification.

This design is represented in the accompanying engraving.

The general configuration of the vase is circular. The base *a* is cylindrical, with the coves *b* *e*, astragal molding *c*, bead *d*, and circular bottom *f* to the elliptical body of the vase, as shown. Around the body there are the moldings at *h* and *k*, the latter being wreathed with leaflets. The upper part of the vase is coved at *l*, the surface of which is ornamented with a wreath of leaves. The top is molded at *m*, as represented. Upon the surface of the vase are reeds *n*, rosettes *o*, and flower ornaments *p*, 20 with storks *q* in relief. The handles of the

vase are made with the reverse scroll and leaflet ornaments *r* *s*, with scroll ornaments *t* uniting the outer rib, *u*, to the body of the vase, as shown.

I claim as my invention—

1. The design of the shape and configuration of the elliptical body and molded base and top of the vase, as represented. 25

2. The design of the ornamental reeds, rosettes, and storks in relief on the surface of the vase, substantially as represented. 30

3. The design of the scroll and leaflet handles, substantially as represented.

Signed by me this 20th day of December, A. D. 1882.

WILLIAM TWEEDDALE.
